UNITED STATES PATENT OFFICE.

WILLIAM J. MACPHAUL, OF NEW YORK, N. Y.

DESIGN FOR A PAPER DOILY.

Application filed October 16, 1928. Serial No. 28,511. Term of patent 14 years.

To all whom it may concern:

Be it known that I, WILLIAM J. MACPHAUL, a citizen of the United States of America, and resident of the city of New York, county of New York, and State of New York, have invented a new, original, and ornamental Design for Paper Doilies, of which the following is a specification, reference being had to the accompanying drawing, forming part thereof.

The figure is a plan view of a paper doily, illustrating my new and ornamental design.

I claim:

The ornamental design for a paper doily as shown.

WM. J. MACPHAUL.
